Edward R. Lissman
ATTORNEY.

UNITED STATES PATENT OFFICE.

HARRY J. FINCH, OF OIL CITY, PENNSYLVANIA.

VALVE FACING AND RESEATING TOOL.

Application filed February 12, 1923. Serial No. 618,582.

To all whom it may concern:

Be it known that I, HARRY J. FINCH, a citizen of the United States, residing at Oil City, in the county of Venango and State 5 of Pennsylvania, have invented certain new and useful Improvements in Valve Facing and Reseating Tools, of which the following is a specification.

The object, construction and operation of 10 my improved valve facing and reseating tool are herein set forth with sufficient clearness to enable those skilled in the arts to which its construction and use respectively relate, to make and use the same.

15 This tool is intended especially for use with poppet valves such as are employed in internal combustion motors, and is adapted for the simultaneous refacing of both the valve and its seat. It can, however, 20 be used to reface either the valve or its seat separately if desired.

Both the construction and the method of using the tool are illustrated in the accompanying drawings, in which:

25 Fig. 1 is a plan view of the tool as it is assembled for the purpose of refacing a valve alone.

Fig. 2 is a central, vertical section of the tool.

30 Fig. 3 is a side elevation of the cutter-head.

Fig. 4 is a half-sectional-elevation of the centering ring.

Fig. 5 is an elevation of the cutter-head 35 actuating sleeve.

Fig. 6 is an elevation of the feed nut.

Fig. 7 is an elevation of the combined feed-screw and valve holder.

Fig. 8 is a central, vertical section of my 40 device, and the related portion of a motor cylinder, when the tool is used for simultaneously facing both a valve and its seat.

Fig. 9 is a side elevation of the upper portion of a feed actuating element corresponding to a valve, which is used when only 45 the seat is being re-faced.

The construction shown in said drawings is substantially as follows:

The cutter-head which is employed in this 50 tool, is shown in side elevation in Fig. 3. The upper portion of this head is tubular and the lower portion of same is formed into downwardly-converging walls 1: two opposite quarters of said downwardly-converging walls are removed and to both edges

of the remaining quarters is suitably attached a cutter 3, 3, 3, 3; said cutters 3 are of greater width—in their vertical dimension—than the thickness of the walls to which they are attached, so that a cutting 60 edge is presented which projects above the upper face of said wall and below the lower face of same. The cutting edges of each cutter are parallel and are disposed at an angle to the axis of the cutter-head: this 65 angle corresponds to the angle of the valve seat to be faced and to the angle of the seating face of the valve, so that, after said valve and said seat have been re-faced said valve will seat truly upon said seat. 70

When said cutter-head is to be used for re-facing the valve only, it is carried by a bracket 4, which is attached to the edge of a work-bench 5, as shown in dotted lines in Fig. 2. 75

Said bracket comprises a circular, horizontally-disposed base-plate 6, the upper face of which is machined and accurately finished. Formed integrally with said base and projecting below the same is a guide-socket 7 through which a hole is formed concentrically with and perpendicularly with the upper face of said plate. A bushing 7' may be inserted in said hole which may be changed to accommodate stems of differing 80 diameters. A centering ring, Fig. 4, indicated by the ordinal 8 is placed upon said plate 6 and is free to be revolved thereon. The upper face of said ring 8 is formed at an angle corresponding to the angle of said 85 cutters 3. Said cutter-head is carried by said plate 8 with the lower edges of the cutters resting upon its slanting, angular face. The upper, cylindrical portion of said cutter-head is provided with two outwardly, 90 horizontally extending, diametrically disposed pins 9, 9, to be engaged for the purpose of revolving said cutter-head. For the purpose of engaging said pins 9 and revolving said cutter-head a driving sleeve 10, 95 Fig. 5, is provided which has as features thereof two vertically disposed slots 11 extending upwardly from its lower edge to receive said pins 9. The upper end of said sleeve 10 projects above said cutter head 100 and its upper edge is provided with a plurality of downwardly-extending notches 12 for the reception of a bar 13 whereby the cutter head may be revolved.

The upper face of said plate 6 adjacent 110

its periphery is provided with a concentric ledge 14 and keeper 15 which serve to support and centralize said sleeve 10.

When a valve, as indicated in dotted lines 5 in Fig. 2, is to be refaced, its stem 16 is inserted through the guide-socket 7 with its lower end projecting below said socket. A tubular feed screw 17, Fig. 7, is then connected to the lower end of said stem by the 10 insertion of said stem into the hole of said screw and then screwing up the lever 18 so that its inner point bears against said stem 16 and firmly clamps the same non-revolubly within said screw. A tubular feed-nut 19, Fig. 6, is applied to said screw with its upper end in contact with the lower end of said guide-socket 7. By turning said feed-nut so as to exert a downward pull upon said stem, the valve, which is 15 shown in dotted lines in Fig. 2 will be actuated into facing relation to upper, cutting edges of the cutters 3 of said cutter-head.

When the cutting or facing operation is 20 in progress, the lever 18 is, in this case, 25 permitted to rest against any suitable stop, as a pin 20 secured to the work-bench 5, to prevent the valve from being turned by the action of the cutters.

Any desired or necessary amount of metal 30 may be removed from the valve in the facing operation by a suitable actuation of the feed nut 19.

The centering ring 8, in the case illustrated in Fig. 2, turns with the cutter-head.

35 Fig. 8 illustrates the way in which my improved facing tool is used when both the valve and its seat are simultaneously faced.

In this case the guide-ring 8 is dispensed with and its place is taken by the valve-seat 21 of the motor cylinder 22. Also the 40 guide socket is dispensed with and its place is taken and its function performed by the valve-stem guide 23. In this case the lever 18 is stopped against the outer wall of the cylinder to prevent the valve from turning 45 as it is being faced off.

In Fig. 9 is shown a feed-actuating device 50 which is substituted for a valve and its stem when a seat only is being faced. In this device the disc 24 is revolvably mounted upon the stem 25: this device occupies

the same position as does the valve shown in Fig. 8, and the feed-screw 17 is attached to it and actuated as in Fig. 8: when the cutter-head is turned to face the seat, disc 55 24 turns with it.

I claim the following:

1. A valve facing and reseating tool comprising in combination, a cylindrical, revolvable cutter-head having one end thereof formed into converging walls disposed at an angle to the axis of said head corresponding to the angle of the seating face of a valve, cutters carried by said converging walls adapted to reface said seating face 65 of said valve, a guide-ring upon which the lower face of said converging walls seats, a horizontally-disposed plate, upon the upper face of which said guide-ring revolvably seats, a guide socket formed integrally 70 with said plate for the reception of the stem of a valve to be faced, means actuating said valve into facing relation to said cutters and non-revolubly retaining same in said relation, and means for revolving said cutter head to cause its facing action upon 75 said valve.

2. A valve facing and reseating tool comprising in combination, a cylindrical, revolvable cutter-head having one of its ends 80 formed into converging walls disposed at an angle to the axis of the cylinder corresponding to the angle of the seat for a valve and to the face of said valve which seats upon said seat, cutters carried by said converging walls having upper and lower cutting edges whereby a valve seat and a co-operating valve may be simultaneously faced, a guide for the stem of said valve, means arranged to actuate said valve into 85 facing relation to said cutters and said cutter-head into facing relation to said seat, means non-revolubly retaining said valve in 90 said relation, and means for revolving said head to cause said facing operation of said 95 cutters.

In testimony whereof I affix my signature in presence of two witnesses.

HARRY J. FINCH.
